UNITED STATES PATENT OFFICE.

HERMAN W. STEMMERICH, OF PITTSBURG, PENNSYLVANIA.

OIL-CUP.

SPECIFICATION forming part of Letters Patent No. 293,681, dated February 19, 1884.

Application filed October 19, 1883. (No model.)

To all whom it may concern:

Be it known that I, HERMAN W. STEMMERICH, a citizen of the United States, residing at Pittsburg, in the county of Allegheny and State of Pennsylvania, have invented certain new and useful Improvements in Oil-Cups, of which the following is a specification, reference being had therein to the accompanying drawings.

10 My invention relates to an improvement in oil-cups for lubricating machinery; and it consists in a pendulum operating a plunger that at every vibration opens and closes an oil-conduit, as will be fully described herein-after.

15 The accompanying drawings represent my invention.

Figure 1 is a front view of the cup; Fig. 2, a sectional, and Fig. 3 a plan, view of the same.

20 A represents a cylindrical cup outwardly threaded at its upper edge, on which the cap B is screwed. From the bottom of the cup projects a tubular shank, a, with a fixed nut, b, and a screw-thread from the nut to the end.

25 At the outside of the cup, near its bottom, a curved plate, c, in the form of an inverted arc, is attached, both ends d of which are bent forward, and support each a leather cushion, e, fastened to the plate c. From the center 30 of the arc of the plate c protrudes the end of a horizontal shaft, f, to which is rigidly secured a pendulum, P, that oscillates between the cushions e and causes the shaft to vibrate when in motion. The shaft f is journaled in

35 the cup A, and, extending into the interior, carries an oblong block, g, with a laterally-dovetailed groove in its side toward the center of the cup. In the dovetailed groove of the block g is held a sliding nut, i, screwed 40 to the end of a wrist-pin, h, on a line with the shaft f. The wrist-pin passes through the slotted head l of a pitman, k, that, extending toward the bottom of the cup, is there jointed to a plunger, m, which enters the tubular

45 shank a and closes it. The plunger m is cylindrical, but flattened on one side, beginning at the shoulder n, down to its lower end. The cup A, holding the oil, is firmly to be screwed on a stationary part of the machine 50 or other suitable place over or near the parts to be lubricated, so that the oil, when discharged from the lower end of the shank a, drops in the place where it is needed. A pro-

jection, made for the purpose, on a moving portion of the machine, placed to periodically 55 come in contact with the lower end of the pendulum, pushes it sidewise against one of the cushions e, and, passing on, releases it, when, by its own weight, the pendulum returns to its former position. By pushing the 60 pendulum aside the shaft f is slightly turned, and the block g, rigidly attached to it at the inside of the cup, moved from a horizontal to an oblique position, and returned to the former when the pendulum reassumes the perpendicular. The nut i, within the groove of the block g, is but slightly affected by this motion 65 so long as it occupies the center of the block; but when removed sidewise from it and there secured by the wrist-pin h, a rising-and-falling motion is imparted to it, that increases with the distance from the center. The rising-and-falling motion of the nut i is communicated to the wrist-pin h and pitman k, causing the plunger m to rise or descend each time 70 the pendulum swings from its perpendicular. When raised, the flat side of the plunger gives vent for the oil to flow down; but when depressed, the end of the plunger above the shoulder n prevents the outflow of the oil by closing the tube. 75

The slot in the head of the pitman serves to increase or diminish the length of its stroke, and by it the height to which the plunger is to be raised, whereby the quantity of oil 80 escaping through the vent is controlled.

Having thus described my invention, I claim—

1. In an oil-cup, the combination of a pendulum, a shaft which passes through the side of the cup below its top, nut i, block d, wrist-pin h, pitman k, and plunger m, the parts being combined and arranged to operate substantially as shown and described. 90

2. In an oil-cup, the combination of the pendulum P, shaft f, block g, and nut i, substantially as set forth. 95

3. The combination of the nut i, wrist-pin h, pitman k, and plunger m, arranged and operating substantially as described. 100

In testimony whereof I affix my signature in presence of two witnesses.

HERMAN W. STEMMERICH.
